UNITED STATES PATENT OFFICE.

LOUIS H. WALES, OF NEW BRITAIN, CONNECTICUT, ASSIGNOR TO THE RUSSELL & ERWIN MANUFACTURING COMPANY, OF SAME PLACE.

DESIGN FOR A PADLOCK-CASE.

SPECIFICATION forming part of Design No. 31,624, dated October 10, 1899.

Application filed August 17, 1899. Serial No. 727,592. Term of patent 7 years.

To all whom it may concern:

Be it known that I, LOUIS H. WALES, a citizen of the United States, residing in New Britain, in the county of Hartford and State of Connecticut, have invented and produced a new and original Design for a Padlock-Case, of which the following is a specification, reference being had to the accompanying drawing, in which the figure is a perspective of a padlock-case, showing my new design.

The contour of the case in side view is circular, with a curved depression 1 at the top. The contour of an ordinary shackle is indicated in broken lines as projecting from the edge of the case. At the upper left-hand portion is the representation of a cloud 2 with a chain of lightning 3 issuing therefrom. At

one side of the cloud and lightning is the figure of a Grecian soldier 4, leaning over his shield 5, with one hand on the edge of his shield and with a dagger 6 in the said hand. On the face of the shield there are two series 7 7 of ornaments with a space between suitable for receiving the name of the soldier represented.

Having described my invention, what I claim as new, and desire to secure by Letters Patent, is—

The design for a padlock-case as herein shown and described.

LOUIS H. WALES.
